PRESSURE PAD

Albert W. Tondreau, Hollywood, Calif., assignor
to Warner Bros. Pictures, Inc., New York, N. Y.,
a corporation of Delaware

Application October 3, 1936, Serial No. 103,900

6 Claims. (Cl. 95—75)

This invention relates to a continuous film contact printer and particularly to a pressure pad which maintains the proper contact between the negative and positive films at a translation point on a sprocket.

5 An object of the invention is to obtain better contact between films while passing a translation or printing point.

Another object of the invention is to prevent 10 separation of films while passing over a printing sprocket.

A further object of the invention is to maintain constant pressure on films in contact with one another as they approach and leave a printer 15 sprocket.

A still further object is to prevent sprocket teeth modulation at the translation point on a printer sprocket.

In the usual type of contact printers the negative 20 and positive films are advanced in contact with one another over a portion of a large sprocket having teeth which enter the perforations of each film simultaneously. The films are usually advanced from separate supply reels 25 which means that they approach the printing sprocket at different angles so that air may become trapped between them thus separating the films from one another at the printing point. This separation causes blurring and distortion of 30 the print and in the case of film sound tracks, destroys the low frequency components of the sound. The pressure pad of this invention not only prevents this type of distortion but insures a better film contact when the negative film has 35 shrunk more than usual as in the case of old negatives.

Prior printers of this type usually employ pressure shoes in the form of curved metal blocks having a curvature concentric with that of the 40 sprocket and which are brought substantially in direct contact with the outermost film. This type of pad, if operated with sufficient pressure to maintain the films in intimate contact, causes abrasion and scratching of the film while if abrasion is reduced, entrapped air holds the films apart as they pass the printing point. Pad rollers of different types have been used but they ride upon the sprocket which gives rise to sprocket teeth distortion.

50 The present invention utilizes a pad having self aligning and resiliently mounted pressure rollers at the ends thereof which bear upon the films before they reach the sprocket, the films passing over guides which direct the film tangentially onto and off of the sprocket. The tan-

gential positioning of these guides with respect to the sprocket permits a smooth approach of the films thereon which facilitates the entrance of the sprocket teeth into the perforations of the superimposed films. Sprocket teeth distortion is thereby eliminated. The rollers are freely rotatable so they may adjust themselves with respect to the tangential guides and film irregularities and thus maintain a constant pressure on the films. Air pockets are eliminated by the approach roller and both rollers will cooperate to maintain the two films tightly wrapped over the sprocket at the translation point.

The details of the invention will be better understood by reference to the following description 15 read in conjunction with the accompanying drawing in which:

Fig. 1 is a schematic sketch of the essential portions of a printer embodying the invention.

Fig. 2 is a cross-sectional detailed view of the 20 pressure pad and the printing sprocket.

Fig. 3 is a detailed view showing a cross section of one of the rollers, and

Fig. 4 is a cross sectional view of the pressure pad bracket and portion of the sprocket taken 25 along line 4—4 of Fig. 2.

Referring specifically to Fig. 1, 5 is a supply reel of raw positive stock and 6 is a supply reel of negative film from which the print is to be made. The two films are advanced over a 30 sprocket 8, around guide rollers 9 and onto a printing sprocket 10, after passing between pressure pad roller 12 and a tangential guide 13. The two films are maintained in contact on the sprocket 10 until they are taken therefrom between the tangential guide 15 and the pressure pad roller 16, after which they pass around a sprocket 17 to a take-up reel 18 for the positive film and the take-up reel 19 for the negative film. This type of printer is of the continuous type, 40 the light therefor being supplied from a lamp 21, which is diffused to the translation point 22, the sprocket 10 being of the hollow type mounted upon an axle 20. The lamp 21 and sprocket 10 are in a light tight housing 26 to prevent the 45 positive stock from receiving light except at the translation point 22 where the printing of the picture and sound track portions of the films takes place. A pair of adjustable sections 28 and 31 between the sprocket teeth rings control 50 the size of the translation or printing aperture.

The film is maintained upon sprocket 10 by means of the pressure pad generally indicated at 55 23 and which is supported upon a bracket 24 pivoted at 25. A handle 27 is used for opening

and closing the assembly. The bracket 24 has an extension 29 to which is attached a compression spring 30 for obtaining a certain initial tension of the assembly with respect to the films.

5 Referring now to the detailed views of the pressure pad, the bracket 24 has mounted thereon a curved shoe 35 held in position by means of four screws 37. This shoe has a curvature concentric with the sprocket but positioned five or six film 10 thicknesses therefrom so there will be no abrasion and forms a light block when the assembly is in printing position. The shoe carries at its ends hollow sleeves 38, each maintained in position by pins 39 about which they pivot. These 15 sleeves accommodate T-headed studs 41 which are encircled with grooves 42, as shown clearly in Fig. 2. By means of these grooves and co-operating pins 43, the studs 41 are maintained longitudinally in sleeves 38 but may rotate therein within limits defined by pins 52 attached to studs 41 and slots 53 in the sleeves 38.

Within the T-heads are ball bearings 45 (see Fig. 3) which carry shafts 44 for rollers 12 and 16. The rollers have large diameter end portions 25 which contact the film and are held onto the shafts by respective screws 50. By permitting the rollers to rotate on studs 41, they are self aligning.

The film is directed onto the sprocket 10 by 30 means of the tangential guide 13 and directed off of the sprocket by the tangential guide 15. These guides are fixedly attached to the frame or housing 26 by suitable screws or bolts not shown. It is to be noted that there is a separation between 35 the films as they approach the guide 13 and with the old type of pad, air was usually trapped there-between so that they remained separated as they passed the translation point. In this instance, however, rollers 12 bear against the films as they 40 pass over the guide 13 and roll out any entrapped air, thus bringing the films in intimate contact before they arrive at sprocket 10. The guide 15 directs the film tangentially off of the sprocket while the rollers 16 cooperating with rollers 12 45 maintain the two films in intimate contact and tightly wrapped around the sprocket particularly at the translation point 22.

To provide resiliency in the pressure of the rollers 12 and 16 on the films, compression springs 50 58 and 59 each have one end abutting flattened portions of the sleeves 38 and their other ends abutting screws 60 and 61, respectively, these 55 screws being maintained in position by nuts 62 and 63, respectively. Adjustment of the tension of the rollers is made by advancing or backing off the screws 60 and 61, thus varying the pressure 60 on the springs 58 and 59 and consequently on the rollers 12 and 16 as they bear against the films. This resilient mounting permits any irregularities of the film, such as splices, to pass 65 between the guides and rollers without damage to the films, while maintaining a constant pressure thereon. The sleeves 38 are limited in their action toward the sprocket when removed therefrom by underlying portions of the shoe 35 upon which they rest.

In operating the above pressure pad, it is only necessary to remove the assembly 23 from the sprocket by handle 27. The films may then be 70 threaded around the sprocket and the assembly pressed into place, compression spring 30 maintaining an initial pressure of the rollers 12 and 16 against the films. Any further individual adjustment of the pressure of the rollers is accomplished by the screws 60 and 61, respectively, the

roller 12 having preferably a greater pressure on the film than roller 16.

I claim:

1. In a continuous film contact printing machine having a film advancing sprocket, a lamp 5 and a housing for said sprocket and lamp, the combination of a pair of tapered guides adapted to direct negative and positive films tangentially on and off of said sprocket adjacent the translation point, a pair of self-aligning rollers adapted 10 to bear said films against said guides, means for individually predetermining the pressure of each of said rollers on said films, a bracket for mounting said rollers, and means for resiliently exerting a pressure on said bracket. 15

2. In a continuous contact film printer having a continuous rotatable sprocket adapted to advance a plurality of films in contact thereover, the outermost film being a positive to be printed and the innermost film a negative, and a lamp 20 for providing printing light for transmission through said negative to said positive, the combination of guides positioned adjacent the circumference of said sprocket for directing said films onto and off of said sprocket tangentially 25 with respect to the circumference thereof, rotatable means for pressing said films against said guides, and means for individually varying the pressure of each of said rotatable means. 25

3. In a continuous contact film printer, the 30 combination in accordance with claim 2 in which said last mentioned means comprises adjustable screws having compression springs interposed between them and said rotatable means.

4. In a printer, the combination of means consisting of a sprocket adapted to engage and advance a pair of films in contact past a printing point on the circumference of said sprocket, a guide adjacent said sprocket adapted to direct said films in a path onto said sprocket, said guide 40 terminating in said path in advance of said sprocket, a support, an arm pivoted on said support, a roller mounted on said arm adapted to bear said films against said guide, resilient pressure means between said support and said arm 45 for urging said roller against said films, and means for adjusting the force of said resilient pressure means. 35

5. In a continuous contact film printer having a continuous rotatable sprocket adapted to advance a plurality of films in contact thereover, the outermost film being a positive to be printed and the innermost film a negative, and a lamp 50 for providing printing light for transmission through said negative to said positive, the combination of guides positioned adjacent the circumference of said sprocket for directing said films onto and off of said sprocket tangentially 55 with respect to the circumference thereof, a light block between said guides, a pair of oppositely extending roller mountings projecting beyond said block, means for pivotally securing the inner ends of said mountings to said block, a self-aligning roller at the outer end of one of said mountings for pressing said films against one of said guides, a self-aligning roller at the outer end of the other of said mountings for pressing said films against the other of said guides, and tensioning 60 means for said mountings, said light block having a curved shoe at each side thereof adjacent the opposite rows of sprocket holes in said films, said light block between said shoes being substantially free from frictional engagement with the outermost one of said films. 65

6. In a printer, the combination of a light block having curved shoes at opposite sides thereof, a slot extending through each end of said light block, a pin in each of said slots, an arm in each of said slots and pivotally mounted on each of said pins, said arms projecting outwardly from said light block in the general direction of the

curvature of said shoes, a self-aligning roller on each of said arms, a bracket secured to said block and extending over said slots, a spring barrel in said bracket opening into each of said slots, and a spring for each of said spring barrels.

5

ALBERT W. TONDREAU.
